UNITED STATES PATENT OFFICE

DEAN M. SOLENBERGER, OF CLEVELAND, OHIO, ASSIGNOR TO THE SIMPLEX PISTON RING COMPANY OF AMERICA, INC., A CORPORATION OF OHIO

DEVICE FOR REDUCING PISTON SLAP IN INTERNAL COMBUSTION ENGINES

Application filed September 24, 1928. Serial No. 307,978.

This invention relates to devices for reducing slap of pistons which loosely fit their cylinders and of that type in which one side of the piston is held in contact with one side 5 wall of the cylinder. Heretofore, devices of this character have been made in which the piston is held in eccentric relation to the cylinder through the medium of a piston ring, together with means for exerting resilient pressure between the ring and the 10 piston with a preponderance of said pressure in one direction. The means employed for exerting this resilient pressure is preferably a corrugated ribbon expander which lies between the inner surface of the ring and the 15 bottom of the ring groove. The preponderance of pressure in one direction may be produced either by the use of an eccentric ring, that is, a ring that is thicker on one side than 20 the other, or by an expander which on one side thereof is more rigid than upon the opposite side so as to exert a higher pressure. Inasmuch as the greater tendency toward 25 slap is in the plane of the piston rod, due to the angularity of this rod, it has been found desirable to press the piston against the wall of the cylinder in a direction at right angles to this plane or substantially in the line of the axis of the wrist pin. However, if the 30 ring and expander are free from the piston there is danger that during the operation of the engine they may rotate within the ring groove so that the original direction of preponderance of pressure will be altered. It 35 is the object of the present invention to prevent any shifting of the direction in which the preponderance of pressure is exerted, which I have accomplished by the construction as hereinafter set forth.

40 In the drawings:

Figure 1 is a central longitudinal section through an engine, cylinder and piston to which my improvement is applied.

Figure 2 is a sectional plan view thereof. 45 Figure 3 is a view similar to Figure 2 showing a modified construction.

A designates a piston which is provided with a ring groove B which is preferably arranged adjacent to the plane of the wrist pin 50 C. D is a ring located in the groove and E

is a corrugated ribbon expander which is placed in the groove between the ring and the bottom of the groove to exert a radially outward pressure on said ring. The preponderance of pressure in one direction may be produced in various ways, as for instance as shown in Figure 2 where the ring D is shown as eccentric or radially thicker on one side D' than on the diametrically opposite side D². This will cause a greater compression of the corrugated expander E on the thick side of the ring with the result that the piston will be forced over to the diametrically opposite side of the cylinder and yieldably held in contact therewith. In the construction shown in Figure 3 the preponderance of pressure is produced by a corrugated ribbon expander having the portion E' on one side of greater thickness than the portion E² on the diametrically opposite side. Thus the thick side 60 of the expander is much more rigid than the thin side and will exert a correspondingly greater pressure against the ring.

With the construction as thus far described, the direction in which the preponderance of pressure is to be exerted is determined by the position of the ring on its expander in the ring groove, but there is danger that during the operation of the engine this direction may be changed by the rotation of the ring or expander in the groove. Such a result I have prevented through the use of means for anchoring either the ring or its expander against any relative rotary movement with respect to the piston. Preferably this is accomplished through the attachment of a pin F to the expander or to the ring and engaging the projecting end of this pin with a recess G in the piston shown in Figure 3. Where, however, an eccentric ring is used as shown in Figure 2, the pin F is preferably provided with an oppositely projecting portion F' for engaging a recess in the ring D thereby holding both the expander and the ring from rotation.

It is obvious that in place of the pin F shown any projection from the ring or expander which has an anchoring engagement with the piston will answer the same purpose. Also in place of the specific means shown in

Figures 2 and 3 for causing the preponderance of pressure in one direction any other suitable means for producing such a result may be used.

- 5 In operation the ring D being split is free to readily expand under the pressure of the ribbon expander so that all portions of the periphery of the ring will force in contact with the walls of the cylinder. The preponderance of pressure is, however, in the direction of the axis of the wrist pin and the anchoring means shown prevents any shifting of the direction of such pressure.

10 However, as clearly shown in the drawings, the pin F does not closely fit the recess G but has a slight clearance or a lost motion therein. This permits the breathing movement of the expander which is necessary when the piston moves up and down a tapered cylinder and 20 thus prevents overstressing and breaking of the expander at the pin.

15 What I claim as my invention is:

20 1. A device for preventing piston slap in loosely fitting cylinders comprising in combination with the piston having a ring groove, of a ring engaging said groove, a corrugated ribbon expander between said ring and the bottom of the groove, means by which a preponderance of radial pressure is exerted by 25 said expander in one direction, and means loosely engaging said piston and said ring and expander at one end thereof for holding the same from circumferential displacement.

30 2. A device for preventing piston slap in loosely fitting cylinders comprising in combination with the piston having a ring groove, of a ring engaging said groove, a corrugated ribbon expander between said ring and the bottom of the groove, means by which a preponderance of radial pressure is exerted by 35 said expander in one direction, and means loosely engaging said piston and connected to said expander at one end thereof for holding the same from circumferential displacement.

40 3. A device for preventing piston slap in loosely fitting cylinders comprising in combination with a piston having a ring groove, of a ring engaging said groove, a corrugated ribbon expander between said ring and the 45 bottom of the groove, said expander being of greater thickness in one portion than in another to exert a preponderance of radial pressure in one direction and means loosely engaging said piston and connected to one 50 end of said expander for holding the same from circumferential displacement.

55 In testimony whereof I affix my signature.

DEAN M. SOLENBERGER.
